[57] CLAIM

The ornamental design for a hat or-the like, substantially as shown and described.

DESCRIPTION

FIG. 1 is a perspective view of the decorative hat, or the like, showing my new design;

FIG. 2 is a top plan view thereof;

FIG. 3 is a front elevational view thereof;

FIG. 4 is a side elevational view thereof, the opposite side having an identical appearance to the side view shown;

FIG. 5 is a rear elevational view thereof; and

FIG. 6 is a bottom plan view thereof.
